UNITED STATES PATENT OFFICE.

CLARENCE J. HAMILTON, OF PLYMOUTH, MICHIGAN, ASSIGNOR OF ONE-HALF
TO R. L. ROOT, OF SAME PLACE.

WINDMILL.

SPECIFICATION forming part of Letters Patent No. 250,661, dated December 18, 1881.

Application filed September 14, 1881. (No model.)

To all whom it may concern:

Be it known that I, CLARENCE J. HAMILTON, of Plymouth, in the county of Wayne and State of Michigan, have invented an Improvement 5 in Windmills, of which the following is a specification.

The nature of this invention relates to certain new and useful improvements in the construction of windmills; and the invention consists, first, in the peculiar construction and arrangement of parts, whereby the sails of the wind-wheel are automatically presented to the action of the wind; second, in the peculiar construction and arrangement of parts for throwing 15 the sails out of the wind; and, third, in the peculiar construction, arrangement, and various combinations of the parts, all as more fully hereinafter set forth.

Figure 1 is a perspective view. Fig. 2 is an elevation of the automatic governor and connections therewith. Fig. 3 is a detailed perspective of governor-connections for throwing in and out of wind.

In the accompanying drawings, which form 25 a part of this specification, A represents a suitable turn-table, which is mounted upon a hollow stand-rod, B, which, in turn, is supported by any suitable frame-work. In this turn-table A is journaled the shaft C, in proper bearings; 30 and to the outer end of such shaft is rigidly secured the hub D of the wind-wheel E. To this wheel E are rigidly secured the inner ends of the arms F, which radiate in lines tangential from the periphery of the hub D, and these arms are further secured at the proper distances 35 apart by means of the band G, to which they are rigidly attached. To the outer portions of these arms are pivotally secured the sails H h h', which are of the class usually denominated 40 "double-winged" sails, the smaller ones, h', of which are connected together pivotally by the rods a.

Properly journaled upon the shaft C, and between the hub D and the end of the turn-table, 45 is an elongated plate, I, to each end of which is rigidly secured a bar, J, the outer end of each of which is connected by means of a link or rod, b, to the smaller portion, h', of one of the sails, H, as is clearly shown in Fig. 2. Each

of these bars J has pivoted to or near its outer end a lever, K, the outer or longer arm of which is provided with an adjustable weight, L, while the shorter arm is connected by means of a link, c, to one of the arms F, the parts being arranged and constructed as is clearly shown 50 in the drawings. The rear end of the shaft C is connected by any proper means to the pump-rod in such a manner as to impart a reciprocating motion to the same.

Upon opposite sides of the plate I, and near the ends thereof, are pivotally secured the bell-crank levers M, the shorter arms of which impinge against pins e, Fig. 3, which are secured to the wind-wheel E; or such arms may impinge against one of the spokes of the wind-wheel where the construction of the wheel will admit of it. The longer arms of these bell-crank levers M impinge against the face of the annular ring N, which is capable of having a horizontal movement upon the turn-table, and 60 by which it is guided, said ring being secured to a frame, O. It is guided in its movements by the turn-table, which is connected by means of bars P to the yoke R, which, in turn, is rigidly secured to the lever S, which is fulcrumed 65 between projections T from the turn-table. A coil-spring, h'', is secured at one end to the short arm of this lever S, while its opposite end is secured at any suitable point upon the table, and is for the purpose of retaining the 70 annular ring N in its retracted position, as hereinafter described, while the lever S has secured to its longer arm a rod or cable, U, which extends down to within easy reach from the ground, and by means of which the annular 75 ring may be projected for the purposes herein-after explained.

In practice, when the wind is blowing at a moderate force it strikes the sails H upon the side, usually near the rear face of the wheel, and 80 causes the wheel to revolve, and imparts a reciprocating motion to the pump-rod. As the wind increases in force and the wheel has a tendency to revolve with a greater velocity, the weights L will, by centrifugal force, be compelled 85 to assume a line with the bars J, and therefore must necessarily, by the connecting-rods hereinbefore named, draw the sails and 90 95

turn them so that their edges will be presented to the wind, the action of these weights and their connections upon the sails causing them to present a lesser area of their surface to the action of the wind as the latter increases in force. As the wind decreases again the parts assume their normal condition, and are assisted in this action by the coil-springs *i*. When it is desired to throw the sails entirely out of the wind and retain them in that position, the annular ring *N* is projected by pulling down upon the cord *U*, causing the said ring to press against the longer arms of the levers *M*, which, their shorter arms finding resistance upon the pins *e*, causes the plate *I* and its connections to move radially, and thus draw the sails so that their edges will be presented to the action of the wind.

What I claim as my invention is—

1. In a windmill, the sails *H*, consisting of wide wings *h* and narrow wings *h'*, secured to opposite sides of the arms *F*, in combination with the weights *L* and connections, substantially as described, between the weights and sails, whereby the centrifugal action of the weights when the wheel is turning will cause them to move toward the circumference of the wheel to regulate the positions of the sails, as set forth.

2. In a windmill, and in combination with the plate *I* and its connections, substantially as described, the horizontal moving ring *N* and frame *O*, secured to the yoke *R* by means of the bars *P*, said yoke being secured to a lever, *S*, as described, and by means of which the said ring and its frame are projected or retracted for the purpose of operating the lever *M*, fulcrumed on the plate *I*, substantially as and for the purposes set forth.

3. In a windmill, the pivoted sails *H*, provided with wings *h h'*, of unequal area, and connected by rods *a*, in combination with the plate *I*, rods *J*, weights *L*, weight-levers *K*, rods *b c*, and the springs *i*, substantially as and for the purpose specified.

4. In a windmill, the pivoted sails *H h h'*, plate *I*, rods *J*, weights *L*, weight-levers *K*, rods *b c*, and springs *i*, in combination with the lever *M*, the horizontally-sliding ring *N*, frame *O*, rods *P*, yoke *R*, lever *S*, spring *h''*, and cord *U*, substantially as described, and for the purpose specified.

CLARENCE J. HAMILTON.
